DESIGN FOR A LAMP

Carl A. Swanson, Buffalo, and Otto A. Hokanson, North Tonawanda, N. Y.

Application April 25, 1938, Serial No. 76,732

Term of patent 7 years

To all whom it may concern:

Be it known that we, Carl A. Swanson and Otto A. Hokanson, both citizens of the United States, residing at Buffalo and North Tonawanda, in the counties of Erie and Niagara, respectively, and State of New York, have invented a new, original, and ornamental Design for a Lamp, of which the following is a specification, reference being had to the accompanying drawing, forming a part thereof.

Figure 1 is a front elevation of the lamp embodying our design. Figure 2 is a side view thereof. Figure 3 is a top plan view of the same.

We claim:

The ornamental design for a lamp, substantially as shown.

CARL A. SWANSON.
OTTO A. HOKANSON.
